UNITED STATES PATENT OFFICE.

JOHN H. SMITH, OF PHILADELPHIA, PENNSYLVANIA, ASSIGNOR TO WESTINGHOUSE ELECTRIC AND MANUFACTURING COMPANY, A CORPORATION OF PENNSYLVANIA.

AIR EJECTOR.

Application filed March 3, 1921. Serial No. 449,466.

My invention relates to ejectors and particularly to that class of ejectors employed for exhausting non-condensable fluids from condensers, and it has for an object the production of a two-stage ejector apparatus of the character designated which shall be simple in construction and which shall operate with a high degree of economy of steam consumption. It is a further object of my invention to provide an ejector apparatus in which the heat of the gases passing therethrough, the heat of the steam operating the ejectors and the water condensed from these fluids are conserved and delivered to the power unit.

A still further object of my invention is to produce an efficient air separator which is simple and compact in structure and which cooperates with ejectors of conventional types to accomplish the above objects.

These and other objects of my invention, which will be manifest in the further description thereof, are set forth in the following specification and illustrated in the accompanying drawing, in which Fig. 1 is a diagrammatic view of a condenser system constructed in accord with my invention; Fig. 2 is a vertical sectional view of an air separator on the line 2—2 of Fig. 3; Fig. 3 is a similar sectional view on the line 3—3 of Fig. 2; Fig. 4 is a detailed elevation of the ejector arrangement; and Fig. 5 is a diagrammatic view of a modification of the construction illustrated in Fig. 1.

The marked advantage of operating turbines under high-vacuum exhaust conditions has led to the development of turbine constructions capable of utilizing extremely low exhaust pressures. These conditions of operation have imposed added duties upon the condensing apparatus of power plants utilizing turbines as prime movers, and especially upon the air removal apparatus of such plants, since the vacuum pressures, which it is practicable to utilize in low-pressure turbine plants, are, to a large extent, determined by the efficiency of the air removal apparatus.

By the novel construction of my two-stage ejector, I am able to reduce the steam consumption in the operation of my condenser air ejector to approximately one-half of that required for the operation of air ejectors now in use. This result I accomplish by associating an auxiliary condenser, per-

forming a dual function of an inter-cooler and an air separator, with each stage of the two-stage ejector. The cooling and the separation of the moisture from the air during the process of compression greatly reduces the specific volume of the air which must be handled by the ejector device, and, consequently, less energy is required for its removal from the condenser.

My ejector construction also provides means whereby the heat of the motive steam is reclaimed and returned to the plant. The cooling medium for a first stage auxiliary condenser is condensate from the main condenser, which, having absorbed heat from the air and the steam used as a motive fluid in the ejector, is conducted to the feed water tank. An arrangement permitting the return of the condensate from the first-stage condenser unit to the main condenser outlet or hot well is also provided. The water for the cooling spray of the second stage condenser unit is also condensate from the main condenser, which, together with the condensed steam of the second stage ejector is delivered to the feed water tank. Further economy in the operation of the air ejectors is thus attained, since the heat and water content, both of the motive steam used in the ejectors and of the air removed thereby, is carried from the air removing apparatus to the feed water tank of the power plant.

Referring to the drawing for a more detailed description of my invention, in Figures 1 to 4, I have indicated at 10 a surface condenser of the conventional type. It is to be understood, however, that my air ejector apparatus is adapted for use with other types of condensers, as for example, jet condensers. Exhaust steam from a prime mover is admitted to the condenser 10 through the inlet opening 11, and any suitable provision for the removal of air from the condenser may be made, as through an air discharge opening 12 from whence it is conducted through a pipe 13 to a manifold 14. Connected to the manifold 14 by conduits 15, preferably provided with shut-off valves 16, are two or more ejectors 17. The air thus delivered to the ejectors is entrained therein by steam under pressure admitted through inlet pipes 18. The ejectors 17 may be of any conventional type. Each ejector is arranged to discharge through a diffuser 19 and valve 20 into a branch 21 which com-

municates with a manifold 22. A pipe 23 delivers the mixed steam and air from the manifold 22 to a condensing device 25.

The condensing device 25 is composed of 5 a central vertically extending casting 26 having at its upper portion outwardly extending flanges 27, 28, (Figures 2 and 3). Secured to these flanges are two tube sheets 29, 30 which are arranged to receive tubes 10 31, 32 which extend through the central chamber. A horizontally extending partition wall 33 divides the central tube chamber into separated upper and lower compartments. Water boxes 34 and 35 are secured 15 in any suitable manner to the casting 26 at the edges of each of the tube sheets 29 and 30. The water box 34 is provided with a horizontally extending partition 36 in alignment with the partition 33 which divides 20 the water box 35 into separated upper and lower chambers. The water box 35 has a similar horizontal partition wall 37 which likewise divides the water box 34 into upper and lower chambers. A vertical partition 25 wall 38 is provided within the water box 35 and serves to further divide the upper and lower water box chambers into two separated chambers.

The condenser structure thus far described 30 consists of two distinct condenser units separated by partition walls 33, 36 and 37 and comprising an upper condenser unit 40 and a lower condensing unit 41. The upper condenser unit 40 receives cooling water 35 through the inlet opening 42 and discharges it, after traversing in a double pass through the tubes 31, through an outlet opening 43. Mixed air and steam discharged from the 40 conduit 23 enter the central condensing chamber of the upper condenser unit 40 through an inlet opening 44 and dry and cooled air is discharged therefrom through the outlet 45 in the top wall thereof. An outlet 46 is provided for the withdrawal of 45 condensate from the upper condensing chamber, which is preferably led to the hot well of the main condenser by a pipe 47.

Cooling water enters the lower condenser 50 unit 41 through an inlet opening 48 traverses in a double pass through the tubes 32 and is discharged through an outlet opening 49. Situated in the lower portion of the lower condenser unit 41 is a jet condenser apparatus which consists of a water spray 55 pipe 54 and a perforated air pipe 55. A vertically disposed partition 56 extends between the sides of the lowermost compartment over which the condensate flows to a discharge opening 57. An air discharge 60 outlet 58 is provided near the upper portion of the lower condenser unit 41. It will thus be seen that the lower condenser unit 41 is composed of two condensing members, an upper surface condenser and a lower jet condenser.

The air delivered from the outlet 45 of the upper condenser unit 40 is conducted by a pipe 60 to a manifold 61 from which lead two or more branch pipes 62, provided with valves 63, to ejectors 64. Each ejector is provided with an inlet pipe 65 for the admission of steam under pressure and with a discharge connection 66 which conducts the mixed air and steam to a manifold 67. The mixed steam and air is led from the 75 manifold 67 through a pipe 68, preferably provided with a valve 69, to the air inlet nozzle 55 of the lower condenser unit 41.

The cooling water for the condenser units 80 40, 41 is taken from a hot well 70 of the main condenser 10. As illustrated, a pipe 71 leads to a pump 72 which forces the condensate through a pipe 73 to an elevated tank 74. From the tank 74 the condensate is delivered through a pipe 75 and branch 85 76 to the inlet opening 42 of the upper condenser unit 40, circulates through the tubes 31 as cooling water and is discharged through the outlet 43 and a conduit 77 into a feed water tank 80. The water for the 90 cooling spray of the lower condenser unit 41 is also supplied from the tank 74 through the conduit 75 and a branch 81 which is connected to the spray nozzle 54. The outlet opening 57 of the lower condenser unit 95 41 is also connected to the feed water tank 80 through a pipe 82. The heated condensate in the feed water tank 80 may be delivered through a conduit 83 directly to a boiler feed pump, since its temperature is sufficiently high to serve as feed either to a boiler or an economizer.

The cooling water for the surface condenser of the lower condenser unit 41 may be taken from an external source which is at 105 a considerably lower temperature than the condensate of the main condenser, although under favorable conditions it may be supplied from tank 74, as will be hereinafter more fully described in relation to Fig. 5. As shown, the cooling water is supplied 110 through a conduit 90 to a pump 91 and thence conveyed through a pipe 92 to the inlet opening 48 of the lower condenser unit 41 and after traversing the tubes 32 is discharged through the opening 49 and a conduit 95.

Having described the arrangement of an apparatus embodying my invention, the operation thereof is as follows: Exhaust steam is delivered to the condenser 10 through the inlet opening 11. The steam is condensed and the condensate collected in the hot well 70. The air and non-condensable gases are removed through the outlet 12 and conduit 13 to the manifold 14. It is preferable to connect to the manifold 14 at least two ejectors. This arrangement provides a spare ejector in case an ejector, which should be sufficient for normal service, fails, or in 120 125 130 135

case over-load duty is placed upon the condenser during extended periods. Steam under pressure supplied to the ejector 17 withdraws the air from the manifold 14 and consequently from the condenser 10, and discharges the mixed steam and air at an increased pressure into the upper condenser unit 40. Within this unit, the air is separated from the steam and moisture, and its 10 temperature and specific volume greatly reduced. The dry air is delivered through the conduit 60 to the second stage ejector 64 wherein the pressure of the air is further raised to a little above atmospheric pressure and the combined steam and air discharged into the pipe 55 in the lower portion of the lower condenser unit 41. The steam and air entering through the perforated pipe 55 bubbles up through a body 20 of water and through the water spray from the pipe 54. The steam is thereby condensed and the air passes upwardly through the tubes 32 of the surface condenser where its temperature and specific volume is further reduced and where it is freed of any moisture content. It is then discharged 25 through the opening 58 to the atmosphere.

The cooling water for the auxiliary condensers may be supplied from the hot well 30 of the main condenser from which the condensate is preferably forced into a gravity tank 74, from whence it is supplied to the upper condenser unit 40 and to the water spray of the lower unit 41. This condensate from the main condenser having received the heat from the steam and air passing through the ejector apparatus is then conducted to the feed water tank 80 from whence it is delivered to a boiler feed pump. 35

It may be desirable to supply the surface condenser of the lower unit 41 with cooling water at a lower temperature than that of the condensate in the main condenser in order to remove as much of the moisture as 40 possible from the air before it escapes to the atmosphere. This is particularly true in marine installations where it is advantageous to reduce to as great a degree as possible the make-up water which must be added to the power plant. In such installations this external cooling water may well be taken from the sea. As illustrated, cooling water from an external source is forced 45 by a pump 90 through the pipe 92 to the surface condenser of the lower unit 41, where it traverses the cooling tubes 32 and is discharged through pipe 95 to any suitable discharge.

It is within the purview of my invention 50 to supply the surface condensers of both the upper and lower condenser units 40, 41 with cooling water either from an external source or from the hot well of the condenser. Referring to Fig. 5 of the drawing I have 55 shown an arrangement which is essentially

the same as that illustrated in Figs. 1 to 4. Additional provision is made in this embodiment of my invention for supplying the cooling water to the surface condenser units from either an external source or from the condensate tank 74. As shown, a pump 100 receives cooling water from any suitable external source through a pipe 101 and forces it through a pipe 102 and branches 103, 104 to the condenser units 40, 41 from whence it is discharged through pipes 105, 106 to a discharge pipe 107. Cooling water from the condensate tank 74 may be supplied to condenser units through pipe 75 and branches 108 and 109, the former communicating with the pipe 102 leading to the surface condensers and the latter to the jet condenser 54. The valves 110, 111, and 112 are suitably disposed in the pipes 102 and 104 to permit the cooling water to be supplied to the surface condensers from either the external supply pipe 101, or the condensate tanks 74 through pipe 75. The valve arrangement also permits condensate from tank 74 to be supplied to the surface condensers of the upper unit 40 and water from the supply pipe 101 to the surface condenser 41 in the manner described above in reference to Fig. 1.

The operation of the apparatus illustrated in Fig. 5 is in every respect similar to that described above in relation to Figs. 1 to 4. It provides an apparatus which, by the operation of the valves 110, 111, 112, may be adjusted to meet varying conditions of operation. Where condensate alone is employed for effecting the condensation of the steam and the cooling of the air in my ejector apparatus, all of the water employed for this purpose is conserved and its temperature raised suitably for boiler feed purposes. Where water from an external source is employed, in one or both of the surface condensers of the ejector apparatus, some of the heat is dissipated in the discharge water.

Advantages of my system of air removal reside in simplicity and low cost of construction, in economy in steam consumption required to operate the ejectors, in conservation of the heat and water in the air and in the motive steam, and in flexibility of operation, insuring stability and continuity of service under varying conditions.

While I have shown my invention in two forms, it will be obvious to those skilled in the art that it is not so limited, but is susceptible of various other changes and modifications without departing from the spirit thereof, and I desire, therefore, that only such limitations shall be placed thereupon as are imposed by the prior art or as are specifically set forth in the appended claims.

What I claim is:

1. In combination with a condenser having means for the removal of air, an ejector

- connected to the air removal means, an auxiliary condenser for condensing gases from the ejector, means for supplying condensate from the main condenser as cooling water 5 to the auxiliary condenser, and means for delivering the water condensed in the auxiliary condenser to said condensate supplying means.
2. In combination with a condenser having 10 means for the removal of air, a steam-operated ejector connected to the air removal means, an auxiliary condenser for condensing gases from the ejector, means for supplying condensate from the main condenser as cooling water to the auxiliary condenser, and means for delivering the water condensed in the auxiliary condenser to said condensate supplying means.
3. In combination with a condenser having 15 means for the removal of air, a plurality of ejectors, an auxiliary condenser for each ejector, means connecting the ejectors to the air removal means and in series with each other, means for supplying to each auxiliary condenser condensate from the main condenser as cooling water, and additional means for supplying cooling water from an extraneous source to the auxiliary condenser associated with the ejector last in the 20 series.
4. In combination with a condenser having means for the removal of air, a first-stage ejector connected to the air removal means, an auxiliary condenser into which 25 the first-stage ejector discharges, a second-stage ejector connected to the outlet of the auxiliary condenser, a second auxiliary condenser into which the second-stage ejector discharges, means for supplying condensate from the main condenser as cooling water to each of the auxiliary condensers, and means for supplying cooling water from an extraneous source to the second auxiliary condenser.
5. In a pumping apparatus for condensers having air removal means, the combination of a first-stage ejector connected to the air removal means, an auxiliary condenser into which 30 the first-stage ejector discharges, a second-stage ejector connected to the outlet of the auxiliary condenser, a second auxiliary condenser into which the second-stage ejector discharges, means for supplying condensate from the main condenser as cooling water to each of the auxiliary condensers, and means for withdrawing the cooling condensate and the condensate from the auxiliary condensers whereby both the heat and water entering the pumping apparatus are 35 conserved.
6. In combination with a condenser having 40 separate air removal and condensate removal conduits, a steam operated ejector connected to the air removal conduit, an auxiliary condenser into which the ejector discharges, the condensate removal conduit being arranged to supply cooling water to the auxiliary condenser, a pump in the condensate removal conduit and means for conducting condensate formed in the auxiliary 45 condenser to the condensate removal conduit at a point between the pump and the condenser.
7. In combination with a condenser having 50 separate air removal and condensate removal conduits, a steam-operated ejector connected to the air removal conduit, an auxiliary condenser into which the ejector discharges, a second steam-operated ejector connected to said auxiliary condenser, the condensate removal conduit being arranged to supply cooling water to the auxiliary condensers and means for withdrawing the condensates whereby both the heat and water involved in the withdrawal and cooling of 55 the air are conserved.
8. In combination with a condenser having a two-stage steam-operated ejector, an auxiliary condenser for the ejector comprising a casing, a horizontal partition dividing the casing into two separate chambers, one of said chambers having end boxes and connecting tubes constituting a surface condenser; the other of said chambers having end water boxes and connecting tubes in the upper portion thereof and a water spray nozzle and vapor inlet in the lower portion thereof and constituting a combined surface and jet condenser, the first-stage ejector discharging 60 into the said one chamber, and the second-stage ejector withdrawing uncondensed fluids from the said one chamber and discharging into the said other chamber.
9. In combination with two steam-operated 65 ejector pumps connected in series, an air separator comprising a casing, a horizontal partition dividing the casing into two separate chambers, one of said chambers having end water boxes and connecting tubes and constituting a surface condenser, a conduit leading to the lower portion of said chamber and receiving the discharge from one ejector, an outlet conduit leading from the top thereof to the second ejector; the other of said 70 chambers having end water boxes and connecting tubes in the upper portion thereof, a water spray pipe in the lower portion thereof, a second spray pipe below the water spray pipe and connected to receive the discharge from the second ejector, and an outlet in the upper portion of the said other chamber.
10. In combination with two steam-operated 75 ejector pumps connected in series, an air separator comprising a casing, a horizontal partition dividing the casing into two separate chambers; one of said chambers having end water boxes and connecting tubes and constituting a surface condenser, a conduit leading to the lower portion of said chamber 80
- 110
- 115
- 120
- 125
- 130

an outlet conduit leading from the top thereof to the second ejector, a condensate discharge leading from the bottom thereof; the other of said chambers having end water boxes and connecting tubes in the upper portion thereof, a water spray pipe in the lower portion thereof, a second spray pipe below the water spray pipe and connected to receive the discharge from the second ejector and an air discharge opening in the upper portion and a water discharge opening in the lower portion of the said other chamber.

11. In combination with a condenser having means for the removal of air, a first-stage ejector connected to the air removal means, an auxiliary surface condenser into which the first-stage ejector discharges, a second-stage ejector connected to the outlet of the auxiliary condenser, and a second auxiliary condenser into which the second-stage ejector discharges, said second auxiliary condenser having tubes through which a cooling fluid is circulated, and a jet by and receiving the discharge from one ejector,

means of which cooling fluid is brought into 25 contact with the fluid to be condensed.

12. In combination with a condenser having means for the removal of air, a first-stage ejector connected to the air removal means, an auxiliary surface condenser into 30 which the first-stage ejector discharges, a second-stage ejector connected to the outlet of the auxiliary condenser, a second auxiliary condenser into which the second-stage 35 ejector discharges, said second auxiliary condenser having tubes through which a cooling fluid is circulated and a jet by means of which cooling fluid is brought into contact with the fluid to be condensed, and means for supplying condensate from the main condenser as a cooling fluid to the first auxiliary condenser and to the jet of the second auxiliary condenser.

In testimony whereof, I have hereunto subscribed my name this 25th day of February, 1921.

JOHN H. SMITH.

Certificate of Correction.

It is hereby certified that in Letters Patent No. 1,611,689, granted December 21, 1926, upon the application of John H. Smith, of Philadelphia, Pennsylvania, for an improvement in "Air Ejectors," errors appear in the printed specification requiring correction as follows: Page 4, line 130, claim 10, after the word "chamber" insert the words *and receiving the discharge from one ejector*; page 5, line 24, claim 11, strike out the words "and receiving the discharge from one ejector"; and that the said Letters Patent should be read with these corrections therein that the same may conform to the record of the case in the Patent Office.

Signed and sealed this 1st day of February, A. D. 1927.

[SEAL.]

M. J. MOORE,
Acting Commissioner of Patents.
